UNITED STATES PATENT OFFICE.

EDWARD H. HEBERN, OF OAKLAND, CALIFORNIA.

DIRECTION-SIGNALING DEVICE.

1,374,450.

Specification of Letters Patent. Patented Apr. 12, 1921.

Application filed September 26, 1916. Serial No. 122,208.

To all whom it may concern:

Be it known that I, EDWARD H. HEBERN, a citizen of the United States, residing at Oakland, in the county of Alameda and 5 State of California, have invented new and useful Improvements in Direction-Signaling Devices, of which the following is a specification.

The present invention relates to improvements in devices for preindicating the fact 10 that a driver of a vehicle is about to turn the same, and the direction in which he is going to turn.

One object of the invention is to provide 15 a device of this character, which can be operated voluntarily from the steering wheel of a motor car as well as automatically by the movement of the steering post, and which will be automatically returned to 20 normal position by the turning of the steering post to normal position.

A further object is to provide a device 25 with which it will not be necessary for the driver of the motor car to devote his attention to the signaling device after once starting the same toward the proper indicating position until it has been moved to said position.

A further object is to provide an improved 30 means for substituting the signaling device for a radiator cap.

A further object is to provide an improved radiator cap.

A further object is to provide improved 35 mechanism for exhibiting at the same time a lamp, a number plate and a preindicating signal, both of which latter are illuminated by the former.

Further advantages of my invention will 40 appear from the description thereof and will be particularly pointed out in the claims.

In the accompanying drawings, Figure 1 is a vertical transverse section of my improved preindicator looking from the rear; Fig. 2 is a vertical longitudinal section thereof; Fig. 3 is a section on the line 3—3 of Fig. 1; Fig. 4 is a horizontal section on the line 4—4 of Fig. 3; Fig. 5 is a broken 50 side view, partly in section, showing a modification of the means for securing the preindicator in place; Fig. 6 is a side view, showing the preindicator applied to the rear of a car.

Referring to the drawing, 1 indicates a radiator tube, extending upwardly through

a hole in a radiator casing 2, and adapted to be closed by the usual cap, not here shown. On the top of said tube 1 is screwed a collar 3 having an outwardly extending flange 4 resting upon the inwardly extending flange 6 of a ring 7, which flange and ring rest upon a tube 8 surrounding an upwardly extending cylindrical portion 9 of the radiator casing and resting upon the radiator. By screwing said collar 3 upon said tube 1, the tube 8 can be fitted tight upon the radiator casing.

Resting upon the ring 7 is a plate 11, which is held down to extensions 12 of said ring by bolts 13, 14, the bolt 13 being tubular and passing through a hole in one extension 12 of the ring and in the plate and forming a pivot for said plate, and the other bolt 14 passing through a hole in the other extension 12 of the ring and through an open-ended recess 16 in the plate in one edge of the extension thereof, said bolts having respectively heads 17 and 18 resting upon the plate, and being pressed down by springs 19 coiled around the bolts and compressed between the under side of the plate and collars 21 secured on said bolts. The head 18 has secured therein depending pins 22, which engage sockets 23 in the plate and hold the plate in proper position upon the ring. But, if the bolt 14 and the head 18 be raised, so that said pins 22 are disengaged from the sockets 23, then the plate can be swung about the other bolt 13 as its center. For this purpose the plate is provided with a handle or extensions 24 extending radially from the other bolt 13. To raise the bolt 14 so as to disengage the pins 22 from the sockets 23, there is provided a lever 25 extending laterally in the recess 16 from a point underneath the bolt head 18 over the edge of the adjacent extension of the ring 7, and having a hole through which extends a pin 26 depending from the head 18 of the bolt 14, said pin after extending through the hole in the lever, also extending into a hole 27 in the extension of the ring 7. By depressing the outer end of said lever, the inner end is raised, the hole having rounded or enlarged ends to permit of rotary movement relative to the pin 26, and the head of the bolt is raised sufficiently to raise the pins 22 out of the holes 23 and allow the plate to swing about the other bolt 13 as a center.

To the plate is secured, by screws 28, a

casting 29 forming the base of the casing 31 of my improved preindicator.

In some cars, as, for instance, in Ford cars, the filling tube is attached directly to 5 the radiator casing, or is integral therewith and has an internal thread in which is screwed the cap. In this case, as shown in Fig. 5, a tube 32 having external threads is screwed into the internal threads of the 10 filling tube.

Fig. 6 shows the means of support at the rear of the car. In this case a casting 33 forms a base for the preindicator and has a central depending lug 34, which is pivoted, 15 as shown at 36, to a standard 37 on a plate 38 secured by bolts 39 to the mud guard 41 at the rear of the car, preferably on the left-hand side. A pin 35 is driven through a hole in the standard and through any one 20 of a circular series of holes 40 (shown in dotted lines) in the lug, to hold the casting in place. On a rearward extension 42 from said casting 33 is secured a strip 43 carrying a lamp 44 and casting 46 to which is 25 removably attached a number plate 47. The number plate is not mounted centrally of said strip, but in such a manner that its outer end does not project beyond the fender, and is nearer to the strip than the 30 inner end.

The means for supporting the signaling device on the rear end of the car is of such construction as to fit almost any car.

The device which takes the place of the 35 ordinary radiator cap is so constructed as to be adaptable for any style of radiator, the only pieces that have to be varied being the brass ring 8, which may be made larger or smaller in diameter to fit different sizes of 40 tubes 1, and the tube 8 which may be longer or shorter as needed. For a Ford car the thread is formed on the outside of the collar. In fact this device when used simply as a 45 radiator cap, without carrying the signaling system, is much superior to the ordinary radiator cap, which often becomes loose and rattles and is liable to be lost, whereas the present device is always held down tightly by spring pressure to close the filling tube.

50 Upon the base plate are secured thin plates 48 of fiber of greater length than width, and upon them are laid thicker blocks 49 of fiber of the same shape as the plates except that they have therein holes to receive 55 inner brass tubes 51 surrounding cores 52 of solenoids 53. The fiber plates 48 and blocks 49 are held down to the base plate by screws 54. Within the brass tubes at the bottom short cylinders 56 of soft steel are 60 secured to the brass tubes 51 and fiber blocks 49 by transverse pins 57. Surrounding the brass tube at the top in order to keep the solenoid wires 58 in place are collars 59 of fiber secured to the tubes by pins 61 65 which penetrate the sides of the tubes, but

do not pass into the interior thereof. In said tubes 51 can reciprocate cores 52, the upper ends of which are attached to the ends of a leather or other flexible band 63, secured by a screw 64 to a disk 66 on a shaft 67 having its bearing in a post 68 formed integral with the base. 70

On said shaft 67 is a hub 69 which extends through the casing 31 and to which is secured an arm 71 in the form of an arrow. 75 In the periphery of said disk 66 are formed one central notch 72 and two terminal notches 73, in any one of which can be received a latch lever 74 pivoted, as shown at 76, on an extension 77 of said post 68, 80 said arm being also connected by a pin and slot connection 78 to the upper end of a fiber block 79, in which is secured by a cross pin 80, the upper end of a brass rod 81, 85 slidable vertically in a soft steel cylinder 82, and connected to a soft steel core 83, slidable in a brass tube 84 of a solenoid 86 comprising a wire coiled around the tube and confined between fiber rings 87.

When the driver of the vehicle intends to 90 turn to one side or the other he presses a corresponding push button 88, thereby closing an electric circuit which is as follows: from a battery 89 by a wire 91 through an electrically-operated horn 92 to the sole 95 noid 86, then from said solenoid by a wire 93 to the wire 94 through the solenoid 53 corresponding to the push button which has been pressed, then by a wire 96 to said push button and by wires 97 and 98 to the other 100 pole of the battery. Thereby the horn is sounded and the solenoid 86 and said solenoid 53 are energized, causing the corresponding cores to be attracted, the latch lever 74 to be released and the core 52 to 105 be moved into contact with the cylinder 56, by the magnetic attraction of which it is firmly held. The flexible band connected to the core becomes loose on the side connected with the core which has been attracted, and 110 the opposite core still moves upwardly by its own momentum, so that the arrow has a vibratory movement which is of great advantage in attracting the attention of persons in front of, or behind, the vehicle. 115

In order to prevent the core from moving too far upward out of the solenoid there is provided a yoke 101 attached by a screw 102 to the top of the post, and having arms 103 having bumpers 104 which are interposed in the path of the cores and arrest their upward movement. The arrow will, after a period of vibration, come to rest with a recess 73 slightly past the latch 74, and the arrow is directed in the position 120 shown by the dotted lines pointing in the lower direction. Upon removing the finger from the push button, the horn will immediately cease sounding and the butt end of the arrow being heavier than the pointed 125 130

end, the arrow will swing backward toward its normal position, but it will immediately be arrested, after it has traveled through a very small arc, by the latch entering the recess 73 immediately adjacent thereto. The arrow will then be directed in the position shown by the dotted lines pointing in the upper direction.

It is of importance that this signaling device should be made automatically as well as voluntarily, so that the signal will always be shown when necessary, even though the driver through lack of care should forget to do so. With this end in view there is attached to the steering post 106 a plate 107 having fingers 108 which are on opposite sides of a switch 109, pivoted at 111, and having a rearward extension 112, controlled by a spring 113 tending to bring it always back to a central position. Said switch is connected by a wire 99 with the wire 98, and on opposite sides of said switch are contacts 114, connected by wires 116 with the wires 96. It will be seen that as soon as the steering post is turned to turn the machine, one or the other of the fingers 108 engages the switch 109 so as to move it toward one or the other of the contacts 114 and close the circuit through one or the other of the solenoids.

It will be seen from the above description that the signal may be brought back to normal position either by the driver pressing the other push button and then at once removing his finger, or automatically, by the turning of the steering wheel, back to normal position when the switch 109 will be actuated to contact with the other contact 114. The first operation will be performed when the driver has made the signal intending to turn a corner, but changes his mind, and withdraws the signal without making the turn.

Electric lamps are provided for indicating at night time the direction in which the driver intends to turn the vehicle. From opposite sides of the battery lead wires 121, one of them having therein a switch 122, to lamps 123, from which lead wires 124, to contacts 126 secured to the tops of the brass tubes 51, which contacts are adapted to contact respectively in the descent of the cores 62 with spring contacts 127 supported on the tops of said cores but insulated therefrom by insulating material 128 and from which lead wires 129 to the wires 121.

It will be seen from this construction that if the switch be closed the proper core will be attracted and the proper lamp 123 will be illuminated and indicate the direction in which the driver is about to turn.

The arrow used herein is colored red except in the central portion of the head, which is colored white, there being left a marginal red portion around said white

center and following the outline of the arrow. It is found that an arrow so colored is visible as a signal at a greater distance, either in the day time or at night, than any other. Although the observer may not be able to see the parts of the arrow colored red, yet the white portion of the arrow is distinguishable at a greater distance, and its position in reference to the automobile indicates the intention of the driver.

In order that the horn may sound, the driver must keep his finger on the push button, but it will be observed that when it is not necessary for this to be done, the arrow is still pointed in the signaling direction without the expenditure of any electricity except that required to turn the signal to the proper position.

For the sake of clearness of illustration, the electrical connections have, for the most part, been shown diagrammatically, but the electric wires leading to the horn, suitably located lamps and battery, and then to the solenoids will be contained in a tube 130 leading from the side of the casing into the hollow pivotal bolt 13, and will pass therefrom to the push buttons which are located on the steering wheel, while the contacts 114 and switch 104 are arranged close to the base of the steering post.

My improved mechanism possesses the advantage that very little electricity is required to be expended, for, in the first place, it is only necessary to keep the finger pressed upon the push button until the arrow has come as far as its intended position, in which it is then locked, and the arrow then remains in that position without the further expenditure of electricity; and, in the second place, the only work necessary to be done by the solenoid is to lift the extra weight of the tail of the arrow which is heavier than its head. Also the parts carried by the shaft, namely, the hub and arrow on one side and the disk on the other are arranged to be equally balanced on both sides of the bearing so that these parts rotate easily in the bearing.

I claim:—

1. In combination with a rotatable signaling device, two electro-magnetic means for respectively rotating said devices in opposite directions, locking means for locking the device when it has been rotated to either signaling position, and unitary means for closing the circuit through any one of said electro-magnetic means to energize the same and for withdrawing said locking means from its normal position, said signaling means when rotated by said electro-magnetic means swinging past the position in which it can be locked by said locking means and being weighted to return when free from the control of said electro-magnetic means.

2. In combination with a vibratory di-

- rection-indicating device, solenoids and cores operatively connected to said indicating device to move the same, when the cores are attracted, in opposite directions respectively, said operative connections permitting the device to move independently of said cores.
3. In combination with a vibratory direction-indicating device, solenoids and cores operatively connected to said indicating device to move the same, when the cores are attracted, in opposite directions respectively, said operative connections permitting the device to move independently of said cores, and means for locking said device in its indicating position when the core is no longer attracted.
4. In combination with a vibratory direction-indicating device, solenoids and cores operatively connected to said indicating device to move the same, when the cores are attracted, in opposite directions respectively, said operative connections permitting the device to move independently of said cores, and means controllable both automatically and voluntarily for energizing either solenoid as desired.
5. In combination with a vibratory direction-indicating device, solenoids and cores operatively connected to said indicating device to move the same, when the cores are attracted, in opposite directions respectively, said operative connections permitting the device to move independently of said cores, and means controllable both automatically

and voluntarily for energizing either solenoid as desired, said means operating to withdraw said locking device from its locking position.

6. In combination with a radiator, a cap therefor pivoted to swing in a horizontal plane on one side of the radiator filling tube, said pivot being hollow, springs for depressing said cap to close said filling tube, electromagnetic signaling devices supported by said cap, and a tube extending from said devices through the pivot of said cap and through which lead the electric wires which conduct the currents to said electro-magnetic devices.

7. An automobile signal comprising a pointer mounted on a shaft to extend above and below its axis of rotation and so balanced thereon that it is normally upright but may be easily moved and held to either side, two solenoids mounted upright, a plunger in each solenoid, a flexible member connecting one plunger with the other and passing over the pointer shaft for suspension of the plungers, the plungers being maintained normally in equilibrium, the plungers and the pointer, each, being balanced on the same axis of suspension to produce a coöperating suspension balance between the plungers and pointers, and means for directing a current sufficient to overcome the balance through either solenoid.

EDWARD H. HEBERN
